UNITED STATES PATENT OFFICE.

GEORG ANTON JASMATZI, OF DRESDEN, GERMANY.

CIGARETTE-MAKING MACHINE.

SPECIFICATION forming part of Letters Patent No. 662,940, dated December 4, 1900.

Application filed October 29, 1897. Serial No. 656,794. (No model.)

To all whom it may concern:

Be it known that I, GEORG ANTON JASMATZI, a subject of the King of Greece, residing at Dresden, Saxony, German Empire, have invented certain new and useful Improvements in Cigarette-Making Machines, (for which I have obtained Letters Patent in Great Britain, No. 16,208, dated July 8, 1897; in Austria, No. 47/2,628, dated June 18, 1897; in 5 Hungary, No. 9,851, dated June 23, 1897; in Belgium, No. 130,250, dated August 24, 1897; in Italy, No. 88/26, dated June 26, 1897; in Russia, No. 2,694, dated June 30, 1897, and in Switzerland, No. 15,052, dated August 23, 10 1897,) of which the following is a specification.

The present invention has for its object a cigarette-making machine provided with a suitable system of levers which are operated 20 by any desired means and their movement utilized, on one hand, for pressing down a movable cover or flap over the tobacco-channel or holder and, on the other hand, for the forward-and-backward movement of the plunger, as well as for pressing a finger which 25 holds fast the cigarette paper tube during the time that tobacco is being introduced into it.

In the accompanying drawings, Figure 1 shows the device according to the present invention in elevation, Fig. 2 in plan, and Fig. 3 in rear elevation from the opposite side of the machine from that shown in Fig. 1. Fig. 4 is a cross-section on the line A B, Fig. 1, showing the channel open; and Fig. 5, a similar view showing the channel closed. Fig. 6 35 is a cross-section on the line C D, Fig. 3, showing the operating device and the guide for the driver.

In the machine the tobacco is placed on a 40 plate *b*, arranged on the upper side of the frame, and from this plate is guided in sufficient quantity into the channel *c* the paper tube which is to receive the filling of tobacco being placed over projecting tube *d*. By turning the spindle *e*, which may be effected by 45 hand by means of a lever *f*, as shown in the drawings by way of example, or by foot or mechanically, the hinged cover *g* is turned down, so as to form the tobacco in the channel into a cylindrical roll. The latter movement must take place at certain definite intervals, for the channel must be closed be-

fore the interchangeable driver *h* penetrates into it and must remain closed during the time that the driver remains therein. For 55 this purpose there is arranged on the spindle *e* beside a toothed segment *i*, by means of which the slide *k*, carrying the interchangeable driver *h*, is caused to reciprocate, a cam *l*, on which rests a roller *n*, mounted at the 60 end of a lever *m*. This cam *l* is secured on the spindle *e*. A key *o*, Fig. 6, arranged on the hub of the cam *l*, acts as a tappet for the toothed segment, which is loose on the spindle, the free end of said key engaging with a 65 recess in the hub of the toothed segment *i*. As soon as the spindle *e* is turned toward the left-hand side, as by the handle *f*, as seen from Fig. 1, the slide *k*, with the driver *h*, also moves toward the left—that is to say, 70 toward the channel *c*—and at the same time the end of the lever *m*, pivoted at *m'*, is raised by the cam *l*, said movement being communicated from the other end of the lever to the cam or pivoted lever *p*, whereby the flap *g* is 75 caused to turn downward, so as to completely close the channel *c* into the position Fig. 5. Before the driver *h* penetrates into the channel *c*, charged with tobacco and closed in the above-described manner, the paper tube 80 placed over the tube *d* must be held fast. This is effected in a simple manner by means of a double-armed lever *q*, pivoted at *q'*, on one end of which is arranged a finger *r*, which holds the paper tube as long as the other end, 85 provided with a finger *s*, is pressed out by the rear side of the slide *k*.

In order to enable the finger *r* to hold the paper tube as long as desired, the length of the rear side of the slide *k* is made variable 90 by means of an adjustable bar *t*. This arrangement is advisable to allow cigarettes of different lengths to be manufactured.

The working of the machine is as follows: During the movement of the spindle *e* as the 95 cam *l* is secured to it the lever *m* is caused to move and the flap *g* is closed. Then as soon as the key *o* has passed the recess in the hub of the toothed segment *i* the latter is caused to participate in the movement whereby the 100 slide *k*, with the driver *h*, is caused to move, the lever *q*, with the finger *r*, being also operated. When the spindle turns in the opposite direction, the channel *c* is open and the

driver *h* is withdrawn. The spring *u* on the part *g*, the spring *v* acting on the lever *p* or on the lever *m*, and the spring *w* on the lever *q* must serve to return said parts into their 5 positions of rest.

To avoid resistance to the entering driver *h*, owing to the tobacco becoming clamped in the channel *c* between the plate *b* and the cover *g*, the front edge of the cover *g* and the 10 opposite edge of the plate *b* are sharpened, so that when the cover *g* is closed the projecting tobacco-threads are cut off.

What I claim, and desire to secure by Letters Patent, is—

- 15 1. In a cigarette-making machine, the combination of a channel *c* and a hinged cover adapted to coöperate therewith, of a driver adapted to be reciprocated into and out of the said channel, a slide connected with the 20 driver, a spindle, means intermediate the spindle and the hinged cover whereby the latter will be closed when the spindle is turned, a sector on the spindle engaging with and adapted to reciprocate the slide, and 25 means for effecting the operation of the sector from the spindle at a point in the turning movement of the latter after the cover has been closed, all as and for the purpose set forth.
- 30 2. In a cigarette-making machine, the combination of a channel *c*, and a hinged cover adapted to coöperate therewith, of a driver adapted to be reciprocated into and out of the said channel, a slide connected with the 35 driver, a spindle, means intermediate the spindle and the hinged cover whereby the latter will be closed when the spindle is turned, a sector on the spindle engaging with

and adapted to reciprocate the slide, and means for effecting the operation of the sector from the spindle at a point in the turning movement of the latter after the cover has been closed, a tube arranged to receive and hold a paper tube in position for receiving the tobacco from the channel, a two-armed 40 lever *q*, a finger on one end of said lever adapted to hold the paper tube on its supporting-tube and a finger on the opposite end of the lever *q* adapted to be engaged by the slide as set forth, and for the purpose specified. 45

3. In a cigarette-making machine, the combination of a spindle, the driver *h*, the slide thereof, and the toothed sector engaging with said slide, with a cam-disk *l*, the two-armed 50 lever *m*, a cam or lever *p*, one end of which is adapted to be depressed by the lever *m*, the tobacco-channel *c*, and the cover *g* adapted to be closed by the other end of the cam or lever *p*. 55

4. In a cigarette-making machine, the combination of a spindle, the driver *h*, the slide thereof, and a toothed sector engaging with said slide, with a two-armed lever *q* adapted to be operated by the slide, the tube *d*, a 60 finger on the two-armed lever adapted to hold the paper tube fast on the tube *d*, and means for varying the length of the rear side of the slide, for the purpose specified. 65

In witness whereof I have hereto set my 70 hand in the presence of the two subscribing witnesses.

GEORG ANTON JASMATZI.
